ELECTRIC ADJUSTING DEVICE FOR THE HANDS OF CLOCK MECHANISMS

Application filed July 21, 1930, Serial No. 469,459, and in Switzerland August 12, 1929.

Since the introduction of electricity in the clock industry and for time measuring devices attempts have been made in various ways to ensure the accuracy of the time indication. In master and sub-clock systems, for instance, current impulses are sent out from the master-clock at a given instant by means of a special conductor to the sub-clocks in order to synchronize the latter and radio currents have also been employed for synchronizing purposes.

The invention relates to an electric adjusting device for the hands of a clock movement in which a hand adjusting mechanism is provided with an electro-control magnet having an armature is connected to an operating current circuit, for instance, a lighting circuit and is maintained inactive until its control magnet has been subjected through the supply current circuit to a short variation in its condition of energization, for example, by a short interruption of the operating current at midnight, in order to release the adjusting mechanism and thereby to adjust the hands of the clock movement exactly to the right time of approximately 12 o'clock midnight.

The accompanying drawing illustrates a constructional form of the invention. Figure 1 being a circuit diagram of the arrangement and Figure 2 illustrating the parts of the hands adjusting device connected to a clock movement.

In Figure 1 it is assumed that the hands of an electrically driven clock A are to be adjusted from time to time, say at midnight to exactly 12 p. m. if they do not then indicate that precise time. The clock A for this purpose is provided with an electrocontrol magnet α which has an armature b and which with the driving mechanism of the clock itself is connected by conductors 1, 2 to an operating current main line 3, 4, which may be, for instance, an ordinary lighting main line. The magnet α is maintained constantly energized by the operating current and therefore holds its armature b in its attracted position against the action of the spring b^1 .

Secured to the sleeve c carrying the minute hand of the clock mechanism (Fig. 2) and which is frictionally mounted on the central

arbor, is a toothed wheel e adapted by means of toothed wheels f , g to cause a cam or snail disc h to perform a complete revolution in 24 hours. Adjacent to the periphery of the snail disc h is located the bent arm h^1 of a bell-crank control lever h pivotally mounted at i , the other end of the lever h being provided with a pin l which engages a hook of the armature b . The control lever h is provided with a control spring m and a latch member o is pivotally mounted on the lever h at n , the member o being provided with a pin p , adapted to be engaged by a leaf spring q . The latch member o is adapted to engage with a pin r mounted on the hand adjusting lever t which is pivotally mounted at s . A counter weight arm u tends to maintain the lever t in the normal or inoperative position shown in Fig. 2. The lever t is provided at its upper end with an adjusting fork v which is adapted to cooperate with an adjusting arm w secured to the sleeve c .

If at midnight the operating current is interrupted for a short time, for instance for a fraction of a second, which can be effected for example from a control point by means of a push button switch α (Fig. 1) operated by a distant push button control or other device, the magnet α releases its armature b . The result of this is that since after the expiration of 24 hours the snail disc h has been rotated to such an extent that the control lever h is no longer supported thereby, the control lever h which has now been completely freed by the release of the armature b from the pin l will be rocked under the action of its spring m in the direction of the arrow α and the action of the latch member o carries the hand adjusting lever t forward with a jerk so as to adjust the hand exactly at 12 o'clock midnight by means of its adjusting fork v which engages with the adjusting arm w secured to the sleeve c of the minute hand. If therefore the minute hand has already passed 12 o'clock as shown in dotted lines in Fig. 2, the inner inclined face of the upper arm of the adjusting fork v will come into engagement with the pin w^1 on the arm w and rotates the latter back to the middle position which corresponds to the position

of the minute hand at exactly 12 o'clock midnight.

This correction of the hand is effected almost instantaneously, and towards the end of the movement of the adjusting lever *t* the foot *o*¹ of the latch member *o* engages with a stop *s* mounted on the work-plate, so that, the force of the spring *m* overcoming the tension of the spring *g*, the latch member *o* is released from the pin *r* of the adjusting lever *t* and the latter, is permitted under the action of its counterweight *u* to swing back to its normal position. The armature *b* is again attracted as the interruption of the current was only brief, and during the next 24 hours the rotating snail disc *h* guides the control lever *k* gradually back to such a position that the latch member *o* engages with the pin *r* of the adjusting lever *t* and the control lever *k* is reengaged by means of its pin *l* to the end of the armature *b* in readiness for the next current interruption.

In order to eliminate as much as possible any disturbance of the adjusting mechanism owing to accidental current interruption, the snail disc *h* is provided with a circular locking disc *h*¹ the radius of which is slightly smaller than the radius of the highest point of the cam disc *h*. The disc *h*¹ is arranged to be pressed by spring action in an axial direction towards the snail disc *h* and serves as an additional locking support for the control lever *k* when the latter is in a position ready for release. The disc *h*¹ is provided at a point corresponding to the release point of the snail disc *h* with a narrow slit *h*² in order to permit the rocking movement of the control lever *k* when falling from the highest point of the snail disc *h*.

40 A bevel *h*³ formed on one edge of the slit *h*² permits the disc *h*¹ which rotates with the snail disc *h*, to pass the bent arm *k*¹ of the lever *k*, the disc *h*¹ being resiliently returned during the period while the arm *k*¹ is passing over the periphery of the snail disc *h*.

One advantage of the arrangement above described is that no special control circuit is required, since for instance, an ordinary light main can be employed, and the conditions are particularly simple if the clock mechanism itself is already provided with an electric drive so that a current circuit is already available. Obviously it is possible to adjust any desired number of clock mechanisms by means of the device.

Arrangements could also be devised whereby the control magnet is normally deenergized and during which time the hand adjusting mechanism remains inoperative until current is supplied thereto for an instant from the supply circuit, the armature being thereupon attracted to release the hand adjusting device for operation.

What we claim is:—

65 An electric driven clockwork, compris-

ing an operating current circuit therefor, a hand adjusting lever, an electro control magnet having an armature, said magnet being connected in the same operating current circuit as the clockwork to be energized thereby, an interconnecting control lever between the armature of said control magnet and said hand adjusting lever, a snail disc arranged to be operated by the clockwork and to control the operation of said interconnecting control lever in dependence of time, a device for briefly varying energization of said control magnet, a spring urged latch member for releasably coupling said interconnecting control lever with the hand adjusting lever in combination with a stop so arranged as to produce disengagement of said latch member when adjustment of the hand has been made and to thus allow the hand adjusting lever to return to its normal position.

In witness whereof we have hereunto signed our names.

CHARLES ROSAT.
JAKOB OTTO MOSER.
PAUL REYMOND.
